(57) CLAIM

The ornamental design for a display screen or portion thereof with icon, as shown and described.

DESCRIPTION

FIG. 1 is a front view of a display screen or portion thereof with icon showing our new design; and, FIG. 2 is a second embodiment thereof. The broken lines showing the display screen or portion thereof in both views and the graphical element in FIG. 2 form no part of the claimed design.

1 Claim, 1 Drawing Sheet

FIG. 1

FIG. 2
